UNITED STATES PATENT OFFICE.

GEORGE B. POINDEXTER, OF BREMERTON, WASHINGTON.

COMBINATION-LOCK.

1,339,668.

Specification of Letters Patent. Patented May 11, 1920.

Application filed October 30, 1919. Serial No. 334,624.

To all whom it may concern:

Be it known that I, GEORGE B. POINDEXTER, a citizen of the United States, residing at Bremerton, in the county of Kitsap and State of Washington, have invented 5 a certain new and useful Improvement in Combination-Locks, of which the following is a specification.

My invention relates to improvements in 10 combination locks and the object of my invention is to provide a combination lock that is simple in its plan of construction and that cannot be tampered with or unlocked by any person not knowing the combination thereof.

Another object of my invention is to provide a combination lock that embodies a maximum of compactness while still retaining all the effectiveness of locks of the 20 combination type.

With the above and other objects in view which will appear as the description proceeds, my invention resides in the novel construction, adaptation, combination and arrangement of parts hereinafter described and claimed.

I accomplish these objects by devices illustrated in the accompanying drawings, wherein Figure 1 is a view in side elevation of a combination lock embodying my invention; Fig. 2 is a view in vertical cross-section taken perpendicular to Fig. 1, illustrating the mechanism of the lock in a locked position; Fig. 3 is a view in vertical cross-section illustrating the mechanism of the lock in an unlocked position; Fig. 4 is a top plan view of the lock in an unlocked position; Fig. 5 is a view in horizontal section taken on line 5, 5 of Fig. 2, showing 30 the mechanism in a locked position; Fig. 6 is a view in horizontal section taken on line 6, 6 of Fig. 3, showing the mechanism in an unlocked position; Fig. 7 is a similar view taken on line 7, 7 of Fig. 3; and Fig. 8 is a 40 view of the various elements which comprise the combination mechanism of my combination lock.

Referring to the drawings, throughout

which like reference numerals indicate like parts, the numeral 1 designates a cylindrical 50 casing which is preferably made in two sections to facilitate the assembling of the elements comprising my device and also for making the various adjustments.

The upper section 2 and the lower section 55 3 of the casing 1 are connected as by screw threads 4.

To fixedly secure my device to a wall or base 5 I have formed on the upper end of the section 2 an annular flange 6 said flange 60 6 being adapted to seat on the outer face of a washer 7 disposed around the section 2 while the inner face of said washer 7 bears on the outer face of the wall 5.

The section 2 is externally threaded as at 65 8, to engage a clamping nut 9, said nut 9 not bearing on the inner face of the wall 5 to thereby secure the device to the aforesaid wall.

Seated in a recess 10 formed in the upper 70 portion of section 2 is a jacket 11 said jacket 11 having an annular flange 12 formed on its upper end, which flange 12 is adapted to seat on the flange 6 of the section 2 both of the 75 said flanges being preferably made of the same diameter.

Superposed on the flange 12 is an annular disk 13 the latter having on its dowels 14 adapted to seat in holes or apertures 15 in the flange 12 of the jacket 11 and similar 80 holes or apertures 16 in the flange 6 of the section 2 to thereby prevent any circumferential movement of these elements with respect to each other.

Superposed on disk 13 is a dial plate 17 85 having an annular flange 18 the latter is adapted to seat in a recess 19 of a ring 20, the ring 20 is formed with a downwardly extending annular flange 21 which is adapted to inclose and retain the various 90 elements in their proper position.

Threaded pins 22 in the flange 21 serve to fixedly secure the ring 20 to the flanges on the jacket and the upper section 2.

Disposed within the upper section 2 ad- 95 jacent to the lower end thereof is an internal

partition 23 which forms a chamber 24 in the section 2 and a similar chamber 25 in the lower section 3.

The partition 23 is provided with a central slot 23^a to permit a passage of the mechanism therethrough, from the lower chamber 25 to the upper chamber 24 and disposed within the chamber 24 and adapted for axial movement therein is a disk 26 having on its lower face a boss 27 and on its upper face a pin or lug 28. The disk 26 is fixedly secured to the lower end of a sleeve 29 as by a screw 30 in the boss 27.

The sleeve 29 is preferably formed on its periphery with flattened portions or faces 31 and on its upper end with a shoulder 31^a said shoulder having on its outer face thereof slots 32 and similar slots 33 disposed at right angles to slots 32.

The stem 34 is mounted within the sleeve 29 and adapted for independent axial and rotary movement therein with respect to the sleeve 29 and on its upper end which protrudes from the said sleeve is formed with a flattened portion or wings 35, the lower edge of said wings being adapted to engage or seat in the slots 32 and 33.

The stem 34 also protrudes from the lower end of the sleeve 29 and is formed on its lower end with a squared portion 36 having a cross-member 37 mounted thereon, said member bearing against a shoulder 34^a formed by the stem 34 and the portion 36.

A helical spring 38 disposed around the stem 34 having its upper end bearing against the lower end of the sleeve 29 and its lower end bearing against a washer 39 on the stem 34 said washer being superposed on the cross-member 37. The spring 38 serves to retain the wings 35 of the stem 34 in the selected slots 32 or 33 on the shoulder 31^a of the sleeve 29 as will be readily understood.

An integral stud 40 projects downwardly from the portion 36 of the stem 34 to form a swivel connection with the upper lug 41 of a yoke 42 the latter being retained on the stud 40 as by a washer 43 and a threaded nut 44.

Disposed in the portion 36 between the cross-member 37 and the upper lug 41 is a distance collar 41^a which serves to retain the member 37 against the shoulder 34^a.

The lower lug 45 of the yoke 42 is fixedly secured to a rod 46 as by nuts 47 engaging the threaded end of said rod. This rod may be attached or connected to any device, not shown, which it is desired to be kept locked.

The lower lug 45 of the yoke 42 when my device is in a locked position, as shown in Fig. 2, is adapted to seat in a conical recess 48 provided in a thimble 49 the latter being disposed in the bottom wall 50 of the lower section 3 of the casing 1.

To prevent axial movement of the thimble

49 the latter is fixedly secured in the wall 50 as by a shoulder 51 on the thimble 49 bearing on the inner face of the said wall and by a screw 52 threaded in the boss 53 on the outer face of the said wall, said screw 70 being adapted to bear against the thimble 49 as shown in Fig. 2.

To prevent tampering with the rod 46 I have provided a tube or conduit 54 through which the rod passes, the upper end of said tube being connected to the thimble 49 as by threads 55 and on its other end to the device to be kept locked.

Superposed within the jacket 11 are the various elements of the combination mechanism of my device, comprising an actuating disk 56, a distance ring 57, an annular disk 58, a distance ring 59, and an annular disk 60.

The actuating disk 56 is formed with a boss 61 on the lower face thereof, said boss 61 being adapted to seat in a circular hole 62 in the bottom wall 63 of the jacket 11.

An axial and substantially rectangular hole 64 is provided in the disk 56 said hole 90 64 conforming to the shape of the periphery of the sleeve 29 to thereby permit a positive connection between the disk and the sleeve for simultaneous rotary movement of these elements permitting independent axial 95 movement of the sleeve in the disk.

An upwardly projecting pin 65 is fixedly mounted on the upper face of the actuating disk 56 said pin being adapted to engage a similarly mounted pin 66 on the lower 100 face of the annular disk 58 during the unlocking operation of the combination mechanism.

The annular disk 58 is formed with an axial circular hole 67 sufficiently large to 105 clear the circular portion of the sleeve 29, as shown in the drawings.

Fixedly mounted on the upper face of the disk 58 is an upwardly projecting pin 68 adapted to engage a similarly mounted pin 110 69 on the lower face of the disk 60 during the aforesaid unlocking operation.

The annular disk 60 is also formed with a similar axial circular hole 70 as provided in the disk 58.

The annular disk 13 is also formed with an axial circular hole 71 as in the disks 58 and 60.

The dial plate 17 is formed with an axial and substantially rectangular hole 72 the latter conforming to the shape of the periphery of the sleeve 29 to thereby form a positive connection between the sleeve and the dial plate for simultaneous rotary movement of the elements while permitting of 125 independent axial movement of the sleeve through the plate.

The dial plate 17 is also provided with suitable graduations 73 on the perimeter thereof said graduations being adapted to 130

register with a fixed zero mark 74 on the stationary ring 20.

Each of the disks 13, 56, 58 and 60 also the bottom wall 63 of the jacket 11 is provided with a hole 75 each hole in the various elements being in alinement and adapted to receive the pin or lug 28 on the disk 26 when the mechanism is in an unlocked position, as shown in Fig. 3.

10 It will be readily seen from the foregoing that it is impossible to withdraw the sleeve 29 as the pin 28 on the disk 26 bears against the under face of the bottom wall 63 of the jacket 11 thereby preventing such withdrawal.

15 In the event that an unauthorized person tampering with the lock is successful in locating the hole 75 in the wall 63 the pin 28 would strike the disk 56 thereby preventing further withdrawal. Further attempts by 20 said person to aline the holes 75 in the various elements would be futile unless the combination is known.

25 However, if the combination is known the numbers of said combination on the plate are brought into proper registration with the fixed zero mark on the ring 20 by manipulating the stem 34 and the sleeve 29 thereby rotating the disk 26, also the actuating disk 56 which in turn picks up disk 58 through the medium of the pins 65 and 66 which in its turn picks up the disk 60 through the medium of the pins 68 and 69, thus alining the holes 75 in the various elements and bringing the pin 28 in registration with the same. The sleeve 29 and the stem 34 may now be withdrawn, and in withdrawing the sleeve 29 and stem 34, the pin 28 will pass through all of the disk elements thereby preventing independent 40 rotary movement of the said disk elements.

45 In the withdrawing of the stem 34 the cross-member 37 passes from the lower chamber 25 through the slot 23^a in the partition 23 to the upper chamber 24; the stem 34 is still further withdrawn to release the wings 35 from the slots 32 on the sleeve 29 and is given a quarter of a turn to seat the wings 35 in the slots 33; this movement 50 turns the cross-member 37 at right angles of the slot 23^a, as shown in Figs. 3 and 7, thus preventing any inward movement of the sleeve or stem while the mechanism is in this position.

55 To lock the mechanism the stem 34 is withdrawn thus releasing the wings 35 from the slots 33; the stem 34 is given a quarter of a turn to permit the wings 35 to seat in the slots 32. This movement brings 60 the cross-member 37 in registration with the slot 23^a thus permitting the sleeve 29 and the stem 34 to move inwardly. The stem 34 may be given a few turns to throw the holes 75 out of alinement.

65 The axial movement of the sleeve 29 and

the stem 34 is transmitted through the yoke 42 to the rod 46 to lock or unlock the device to which it is attached.

Manifestly, changes may be made in the forms, dimensions and arrangement of parts of my invention without departing from the spirit thereof.

What I claim is:

1. In a combination lock, comprising a casing, a stem disposed for rotary and axial movement within the said casing, locking means disposed within said casing, means carried by said stem to operate the aforesaid locking means and means carried by the said stem to engage means on the casing 75 to prevent axial movement of said stem when said stem is in an advanced position.

2. In a combination lock, comprising a casing, a stem disposed for rotary and axial movement within the said casing, locking 85 means disposed within the said casing, means on said stem adapted to operate aforesaid locking means and means carried by the said stem adapted to engage the locking means to retain same in an unlocked 90 position.

3. In a combination lock, comprising a casing, a stem disposed for rotary and axial movement within the said casing, locking means disposed within the said casing, 95 means on said stem adapted to operate aforesaid locking means, means carried by said stem adapted to engage the locking means to retain same in an unlocked position, and means disposed on said stem to engage means on the casing to prevent axial movement of said stem when said stem is in an advanced position.

4. In a combination lock, comprising a casing, a stem disposed for rotary and axial 105 movement within the said casing, locking means disposed within the said casing, means on said stem adapted to operate aforesaid locking means, means carried by the said stem adapted to engage the locking 110 means to retain same in an unlocked position and means on said casing to attach same to a base.

5. In a combination lock, comprising a casing, a stem disposed for rotary and axial 115 movement within the said casing, locking means disposed within the said casing, means on said stem adapted to operate aforesaid locking means, means carried by the said stem adapted to engage the locking means to retain the same in an unlocked position, and means on the said casing adapted to register with graduated means on the aforesaid stem.

6. In a combination lock, comprising a 125 casing, a stem disposed for rotary and axial movement in said casing, a sleeve mounted on the said stem adapted for rotary and axial movement with the aforesaid stem, means carried by said sleeve adapted to be 130

- disengaged from means carried by the stem to permit independent axial and rotary movement of the said stem with respect to the said sleeve, locking means disposed within said casing, means on said sleeve to operate said locking means and means on said sleeve adapted to engage aforesaid locking means to retain the said locking means in an unlocked position.
- 10 7. In a combination lock, comprising a casing, a stem disposed for rotary and axial movement in said casing, a sleeve mounted on the said stem adapted for rotary and axial movement with the aforesaid stem, means carried by said sleeve adapted to be disengaged from means carried by the stem to permit independent axial and rotary movement of the said stem with respect to the said sleeve, locking means disposed within said casing, means on said sleeve to operate said locking means, and means on said sleeve adapted to engage aforesaid locking means to retain the said locking means in an unlocked position, and means disposed within the said casing adapted to engage means carried by the said stem to prevent axial movement of the sleeve and the stem when the latter elements are in an advanced position.
- 20 8. In a combination lock, comprising a casing, a stem disposed for rotary and axial movement in said casing, a sleeve mounted

on the said stem adapted for rotary and axial movement with the aforesaid stem, means carried by said sleeve adapted to be 35 disengaged from means carried by the stem to permit independent axial and rotary movement of the said stem with respect to the said sleeve, locking means disposed within said casing, means on said sleeve to 40 operate said locking means, and means carried by said sleeve to engage means disposed within the casing to prevent axial movement of the sleeve and the stem when the said elements are in a retracted position. 45

9. In a combination lock, comprising a casing, a stem disposed for rotary and axial movement in said casing, a sleeve mounted on the said stem adapted for rotary and axial movement with the aforesaid stem, 50 means carried by said sleeve adapted to be disengaged from means carried by the stem to permit independent axial and rotary movement of the said stem with respect to the said sleeve, locking means disposed 55 within said casing, means on said sleeve to operate said locking means, and means on the said casing adapted to register with graduated means on the aforesaid sleeve.

In witness whereof I hereunto subscribe 60 my name this 25th day of October, A. D. 1919.

GEORGE B. POINDEXTER.
